[57] CLAIM

The ornamental design for a golf accessory holder, as shown and described.

DESCRIPTION

FIG. 1 is a perspective view of the golf accessory holder, showing related accessories in dashed lines for illustrative purposes only and forms no part of my design;

FIG. 2 is a front elevation view of the holder;

FIG. 3 is an end view, the opposite end being a mirror image;

FIG. 4 is a rear view;

FIG. 5 is a top view; and,

FIG. 6 is a bottom view.

FIG. 2

FIG. 3

FIG. 4

FIG. 5

FIG. 6
